UNITED STATES PATENT OFFICE.

ELGIN L. CONKLIN, OF CORNING, NEW YORK.

MILLSTONE-DRESS.

SPECIFICATION forming part of Letters Patent No. 269,015, dated December 12, 1882.

Application filed August 21, 1882. (No model.)

To all whom it may concern:

Be it known that I, E. L. CONKLIN, of Corning, in the county of Steuben and State of New York, have invented certain new and useful Improvements in Millstone-Dress; and I do hereby declare the following to be a full, clear, and exact description of the invention, such as will enable others skilled in the art to which it pertains to make and use it, reference being had to the accompanying drawings, which form part of this specification.

My invention relates to an improvement in millstone-dress for stone or metallic disk mills; and it consists in the combination of curved furrows, which radiate from the eye of the stone, and which are separated from each other by flanges which rise to the level of the land-surface, with radial furrows which extend from the outer ends of the curved grooves or furrows to the skirt of the stone, as will be more fully described hereinafter.

The object of my invention is to provide a dress which is specially adapted to breaking the grain so as to prepare it for further reduction, and in which the furrows are so formed that the stone will work cooler and make more and better middlings than can be obtained in the usual way.

Figure 1 is a plan view of my invention. Fig. 2 is a perspective detail sectional view.

A represents a stone or runner, which may be formed of iron, steel, or other suitable material.

Leading out from the eye of the stone are a number of curved grooves B, which are deeper and narrower at their inner ends than at their outer ends. The flanges D, which separate these grooves, are on a level with the land-surface of the stone, and will be preferably laid out upon an outer circle, though the curve may be greater or less, as may be desired. The curved ribs, or dividing flanges prevent the grain from flowing around the eye and being scoured, and at the same time force it out and spread it in one even and unbroken sheet upon the lands or ribs, where the grains are broken. These curved grooves are made deepest at their inner ends, so that the grain will flow freely into them and follow the direction of the curved flanges or divisions until it reaches the outer ends of the grooves where

they are no deeper than the radial furrows F, which extend out over the stone.

The curved furrows at their outer ends have the radial furrows F extend into them, and the only escape for the grain from the curved furrows is directly into the radial ones. There may be four radial furrows and four land-surfaces to each curved furrow, or there may be a greater number, as may be preferred. The radial furrows are made wider and deeper in proportion to width at their outer than at their inner ends, or may be of equal width and depth, so that the grain will flow freely from the stone without having become heated in the grinding or breaking. These radial furrows are made triangular in shape, being deepest on front edge, a, and rising gradually back to the level of the land-surfaces.

Across the land-surfaces may be made any suitable smaller grooves or corrugations, which will run parallel to the radial furrows, and thus increase the breaking capacity of the stone.

The stones may be run in opposite directions or in the same direction, one running faster than the other; or one may be stationary while the other runs, as is usual with stone or metallic disk mills. This dress is especially adapted to crushing the grain, and thus preparing it to be further reduced. Owing to the construction here shown and described, the stones will work easier and make more and better middlings without heating than can be done in the usual manner.

The radial furrows may have any desired draft even to a reversed draft, from that of the curved furrows.

Having thus described my invention, I claim—

In a millstone-dress, the combination of the curved furrows B, deepest and narrowest at their inner ends, separating flanges D, which rise to the level of the land-surface, and the radial furrows F, substantially as shown and described.

In testimony whereof I affix my signature in presence of two witnesses.

ELGIN L. CONKLIN.
